UNITED STATES PATENT OFFICE.

SAMUEL WALKER, OF LILLE, FRANCE.

FLYER SPINNING FRAME.

Application filed November 30, 1926, Serial No. 151,767, and in France October 20, 1926.

The present invention has for its object a device for removing rapidly and simultaneously all the full bobbins and replacing these bobbins by empty tubes, also rapidly and simultaneously, which device is adapted for use in all flyer spinning frames in which the spindle and the flyer forms one body and is driven from the top, and more particularly in dry or wet spinning frames, 10 doubling frames and machines and spinning frames for hemp, flax, jute and other textile materials.

This device, which may be actuated by hand, by semi-automatic means or automatic means, is of the so-called "vertical" type, that is to say it is of the type in which the full bobbins and the empty tubes are displaced in a vertical plane by the movement of the rise and fall mechanism part 20 parallel to the vertical plane.

The invention consists in the combination of means provided in the spindle plate or rise and fall plate or other equivalent member, for allowing the full bobbins to fall vertically in the vertical plane of the spindles; means for bringing the empty replacement tubes upwards into the vertical plane of the spindles, means for holding the tubes in place upon the spindle plate while 30 they are being filled and for disengaging them when the bobbins are completed, and accessory means for actuating by hand, in a semi-automatic or automatic manner, the various operations for disengaging the 35 points of the spindles from their footsteps as well as for disengaging the tubes with their brake ropes or other equivalent braking means, for receiving the full bobbins removed, for cutting the thread of the full 40 bobbins, etc.

According to one practical embodiment of the invention the means for allowing the full bobbins to fall vertically are obtained by forming sufficiently large apertures in the 45 spindle plate to allow the passage of empty or full tubes, the means for moving the empty tubes vertically upwards and carrying them through the apertures and above the plane of the spindle plate consist in providing below the said spindle plate a rail or plate carrying the replacement tubes and having a vertical motion and the means for retaining the tubes upon the spindle plate 50 while they are being filled and for liberating the completed bobbins and allowing them to fall through the spindle plate con-

sist in an intermediate plate resting upon the spindle plate, upon which intermediate plate are carried the tubes, the said plate being adapted to make a longitudinal, transverse or other movement upon the said spindle plate and comprising sufficiently large apertures to allow the passage of the empty or full tubes which, according to the movements it makes, become placed immediately 60 above in register with the apertures in the spindle plate or close them partly or completely. The accessory means may vary and, for example be such as those described hereinafter.

In order to make the invention clear, one form of the device according to the invention is hereinafter described by way of example and is illustrated diagrammatically in the accompanying drawing, the principal means 70 mentioned above being employed in this form of the invention.

In these drawings:

Figure 1 is a vertical cross-section through a flyer spinning frame, in which the spindles 80 are solid with the flyers and are driven from the top.

Figure 2 is a plan section of a part of the spindle plate.

Figure 3 is a plan view of a part of 85 the intermediate plate which moves on the spindle plate.

Figure 4 is a plan view of one end of the spindle plate and of its intermediate plate while the tubes are being filled.

Figure 5 is a similar view, the plate being in position for allowing the full bobbins to fall vertically through the spindle plate.

Figure 6 is a view of a part similar to that shown in Figure 1 showing an accessory 95 means for taking away the bobbins which fall vertically from the spindle plate.

In these figures: 1 is one of the side frames or standards of a flyer spinning frame each 100 flyer of which is solid with its spindle 3 and is driven from above by means of a wharve 4 over which passes the usual spindle rope.

5, is one of the supporting arms integral with its rising and falling carriage 6 which 105 is given a reciprocating movement along its vertical guide 7 by means of a chain 8 which winds on and off its shaft 9 in the usual manner.

10, is the spindle plate carried by the arms 110 5 of the rise and fall mechanism. This spindle plate comprises apertures 11 (Fig.

2) of dimensions larger than the diameter of a full bobbin. The centres of the apertures coincide with the axes of the spindles 3 to which they correspond in number.

5 The upper face of this perforated spindle plate 10 comprises in this form of the device a wide central longitudinal groove 12 in which is mounted a plate 13 of the same length as the spindle plate 10, which plate is 10 adapted to slide along the said groove 12 making a reciprocating motion of suitable length sufficient to allow apertures 14 to be brought at will either in coincidence over the apertures 11 of the spindle plate 10 or 15 so as to ride over two apertures, the said apertures 14 being formed in series in the said plate 13 (Fig. 3) having dimensions slightly greater than those of the full bobbins and corresponding in number to the spindles, the 20 spaces separating each aperture 14 themselves comprising small apertures 15 the centres of which coincide with the axes of the spindles so as to serve as footstamps or thrust bearings for their points when the 25 whole arrangement is in a working position.

The manipulation of the plate 13 for putting it into a working position (Fig. 4) or for bringing it into position for the removal of the bobbins (Fig. 5) is effected in this 30 ample by hand from the end of the frame, by means of a control lever 16 which enables the said plate 13 to be made to slide along the slideway 12 in the spindle plate 10.

In order to permit the grooved bases 17 35 of the tubes 18, when they are slipped on to the spindle 3, to be engaged with or disengaged all at the same time, from their brake rope 19 which is weighted at 20, each of these ropes, which is connected at one end to 40 the inner edge of the spindle plate 10 passes over the notched edge of a bar 21 mounted parallel to the outer edge of the spindle plate along which it is adapted to slide in such a way that it can be moved to and fro 45 by hand by means of a controlling member, such as a lever 22 mounted at the end of the frame near the control lever 16 provided for the plate 13, the effect of which is to permit, when the tubes are in place upon the spindle 50 plate, either all the brake ropes 19 to be brought simultaneously into contact with the grooves 17 of the tubes (Fig. 4) or to disengage them from these grooves (Fig. 5) when the bobbins are completed and have to fall through the plate spindle 10.

At the end of the frame on the side of which are placed the control levers 16, and 22 is disposed a hand wheel actuating a longitudinal horizontal shaft 23 carrying pinions 24 engaging with racks 25 formed upon the rising and falling carriage 6, in order to make it possible to obtain, apart from the normal rise and fall movement, during the change of bobbins, a slight 60 additional lowering of the spindle plate in

order to be able to disengage the points of the spindles 3 from the bearings or footstamps 15 in the sliding plate 13 and thus enable the latter to be displaced in order to allow the bobbin 18 to fall and the renewal tubes to 70 rise through the spindle plate 10.

On a lower vertical plane, parallel to the plane of the rise and fall carriage 6, are mounted, upon similar guides, other carriages 26 comprising arms 27 supporting a 75 rail or plate 28 arranged parallel beneath the spindle plate 10, the said rail being provided with spindle heads 29 of small height corresponding in number to the spindles 3 and situated in alignment with the axes of 80 the latter, the said heads 29 receiving the bases of the replacement empty tubes 18' the grooved bases of which rest upon cylindrical bases 30 of smaller diameter than that of the bases 17 of the tubes and adapted to serve, 85 when the carriages 26 have been raised, as a means for bringing the said tubes on to the spindles 3 above the plane of the spindle plate 10 in order to permit the said replacement tubes to be placed upon the spindle 90 plate 10 and subsequently retained by the plate 13 during the descent of the said carriages 26 with their rail 28.

The rise and descent of the carriage 26 is obtained in this example by hand, in a similar manner to the additional downward movement of the carriage 6, by means of a hand wheel placed near the other control members and keyed upon a longitudinal shaft 31 carrying pinions 32 engaging with 95 racks 33.

In order to prevent the full bobbins 18 when they are expelled vertically from falling on to the renewal tubes 18' disposed axially beneath them as well as in order to prevent them from becoming damaged or from falling in, the said bobbins are received upon a deflecting plate 34 from which they slide into tube or baskets or else on to a band conveyor running along the frame. 105

This plate or deflector 34 is mounted on a hinge joint in such a way that after having deflected the falling bobbins 18 it is brought back out of the path of the tubes 18' which are ascending towards the spindle plate 10. 115

For this purpose the deflector 34 is pivotally mounted upon pivots 35 secured to the side frames 1. It comprises a bell crank lever 36 adapted to be displaced around the 120 axis of oscillation 35 of the deflector which is controlled by means of a movable cam 37 secured to one of the carriages 26 of the rail 28 carrying the renewal tubes 18'. 125

In the normal position the deflector occupies the position in which it deflects the full bobbins as shown in full lines in Fig. 1. When the bobbins have been removed and the rail 28 rises vertically towards the spindle plate 10, the cam 37, acting upon the le- 130

ver 36, raises it and consequently moves the deflector out of the path of the tubes 18' into the position shown in dotted lines in Figure 1.

5 In order to remove the full bobbins and place the empty tubes into position the device described will operate in the following manner.

First. The bobbins having been filled, the 10 notched bar 21 is displaced by means of the handle 22, the effect of which is to bring the ropes 19 from the position shown in Figure 4 into that shown in Fig. 5, that is to say to move them out of the grooves 17 formed in the bases of the bobbins 18.

Second. The points of the spindles 3 are disengaged from their footsteps 15, formed in the slide plate 13, by making the spindle plate 10 descend slightly by means of 20 the rack and pinion control 23, 24 and 25.

Third. The plate 13 is made to slide from the position shown in Figure 4 into that shown in Figure 5 by means of the lever 16, the effect of which is to bring the apertures 25 14 in register with the apertures 11 in the spindle plate and consequently cause the bobbins to fall on to the deflecting plate 34 from which they pass into the baskets or on to a band conveyor.

30 Fourth. By means of the rack and pinion control 31, 32, 33 the rail 28 carrying the tubes 18' is made to rise vertically, the deflector being at the same time moved back, until the bases of the tubes arrive above the 35 plane of the spindle plate 10, slipping on to the spindles 3, the bases 30 on the rail 28 passing through the centre of the juxtaposed apertures 11 and 14 in the spindle plate 10 and the slide plate 13.

40 Fifth. The slide plate 13 is pushed until the edges of the apertures 14 encounter the bases 30 carrying the tube 18'.

Sixth. The rail 28 is made to descend by reversing the operation of the controlling 45 members, the deflector 34 taking up its deflecting position.

Seventh. The slide plate 13 is pushed to the end of its travel so as to bring the footstep apertures 15 into alignment with the 50 axes of the pins 3.

Eighth. The spindle plate is raised by a reverse operation of the controlling members 23—24—25 thus securing the tubes upon their spindles.

55 Ninth. The notched bar 21 is brought back into its original position thus bringing the ropes 19 into contact again with the grooves in the bases 17 of the tubes 18.

Modifications of details and improvements 60 may be made and the use of equivalent means may be imagined without on that account going outside the scope of the invention.

Thus for example, in the case of the application of the device to frames in which

spindle spacings are small, working upon fibre and therefore fragile yarn, the fall of the bobbins on to the deflector might produce waste. In order to remove this drawback the deflector 34 is dispensed with and 70 replaced by a collecting system which is brought beneath the spindle plate at the moment the full bobbins fall and comprises either tubes or small spindles upon which the said bobbins are slipped, the spacing between these small spindles being the same as that between the spindles 3, this spacing being if required varied by mounting the spindles upon extensible lazy tongs or in any other way, so that the bobbins can be placed 75 directly upon the reels without any handling capable of damaging the yarn on the bobbins.

Figure 6 shows a form of such a collecting device moving horizontally beneath the 80 spindle plate 10.

It consists in mounting upon the end frames 1, horizontal supports 38 upon which are carried the ends of a movable rail or plate 39 parallel to the spindle plate 10 and 90 adapted to move transversely along the rails 38 so as to come either into the vertical plane of the platform 10 or into an external plane parallel to the frame.

This horizontal reciprocating motion of 95 the rail 39 may be obtained by any means, for example by means of racks 40 provided beneath the rail, engaging with pinions 41 keyed upon a control shaft 42 actuated from the end of the machine by a hand wheel 43.

Upon the rail are disposed small spindles 100 44 which are spaced the same distances apart as the spindles 3, so as to receive the bobbins 18.

If the spacing between the small spindles 105 is to be capable of variation the latter are then mounted upon the centres of the pivotally mounted cross levers of a lazy tongs system disposed upon the surface of the rail 39 but any other device may naturally be employed for the same purpose.

In the case of the application of the device to frames in which the spacings are small, the length of the spindles 3 may if necessary be decreased so that they do not pass outside the bases of the tubes, the effect of which shortening will be to obviate the necessity of giving the spindle plate an additional downward movement, rendering consequently unnecessary the second and eighth operations numerated above.

What I claim is:

1. A device for removing full bobbins and replacing them simultaneously by empty tubes, adapted for use in all flyer spinning frames in which the spindles and flyers form one body and are driven from the top, characterized essentially by the combination of means provided for in the spindle plate or equivalent member for allowing the full 125 130

4

bobbins to fall vertically in the plane of the spindles, means for bringing the empty renewal tubes vertically upward in the plane of the spindles, means for retaining the tubes 5 in place upon the spindle plate while they are being filled and for allowing them to fall vertically when they are completed and accessory means for hand semi-automatic or automatic control of the various operations 10 for disengaging the points of the spindles from their footsteps and for disengaging the bases of the full bobbins from their brake ropes, for removing the full bobbins from the path of the empty bobbins and for cutting 15 the yarn.

2. A device for removing full bobbins and replacing them simultaneously by empty tubes, adapted for use in all flyer spinning frames in which the spindles and flyers form 20 one body and are driven from the top, characterized essentially by the combination of means provided for in the spindle plate or equivalent member for allowing the full bobbins to fall vertically in the plane of the spindles, means for bringing the empty renewal tubes vertically upward in the plane of the spindles, means for retaining the tubes 25 in place upon the spindle while they are being filled and for allowing them to fall vertically when they are completed and accessory means for hand semi-automatic or automatic control of the various operations for disengaging the points of the spindles from their footsteps and for disengaging the bases 30 of the full bobbins from their brake ropes, for removing the full bobbins from the path of the empty bobbins and for cutting the yarn, wherein the means for allowing the full bobbins to fall vertically are obtained 35 by forming sufficiently large apertures in the spindle plate to allow the passage of empty or full tubes, the means for moving the empty tubes vertically upwards and carrying them through the apertures and above the 40 plane of the spindle plate consist in providing below the said spindle plate a rail carrying the replacement tubes and having a vertical motion and the means for retaining the tubes upon the spindle plate while they are being filled and for liberating the completed bobbins and allowing them to fall through the spindle plate consist in an intermediate plate resting upon the spindle plate; upon 45 which intermediate plate are carried the tubes, the said plate being adapted to make a longitudinal, transverse or other movement upon the said spindle plate and comprising sufficiently large apertures to allow the passage of the empty or full tubes which, according 50 to the movement it makes, become placed immediately above the apertures in

the spindle plate or close them partly or completely.

3. A device for removing full bobbins and replacing them at the same time by empty 65 tubes according to claim 2, wherein the points of the flyer spindles engage in footsteps provided in the movable intermediate plate between the apertures formed in said plate and thereby prevent the apertures in 70 the movable plate from being made to coincide with those in the spindle plate, and that the said spindle plate is adapted to be given an additional downward displacement by a hand control in order to disengage the points 75 of the flyer spindles from the footsteps in the movable plate and thus permit the latter to slide on the flyer plate and the apertures in the two plates to be made to coincide with each other.

4. A device for removing full bobbins and replacing them at the same time by empty tubes according to claim 2, wherein a notched bar is disposed along the edge of the spindle plate, over which notches pass the trans- 85 verse weighted brake ropes of the bobbins, the said bar being adapted to be moved longitudinally backwards or forwards by hand in order to engage the brake ropes in the base grooves of the bobbins or disengage them 90 therefrom.

5. A device for removing full bobbins and replacing them at the same time by empty tubes according to claim 2 wherein a hinged deflecting plate is disposed beneath the 95 spindle plate for guiding away the full bobbins when they fall through the apertures in the spindle plate, the said deflecting plate being adapted to be subsequently moved out of the path of the ascending empty tubes by 100 the upward movement of the rail by means of a lever and a cam secured to said rail.

6. A device for removing full bobbins and replacing them at the same time by empty tubes according to claim 2 wherein a rail is 105 arranged parallel to and beneath the spindle plate for carrying away the full bobbins, the said rail being adapted to be given a horizontal lateral displacement by means of a rack and pinion controlled by hand, said rail comprising small spindles for receiving the full bobbins falling from the flyer spindle through the apertures in the spindle plate, which small spindles may be fixed apart at distances corresponding to those between the flyer spindles or may be adapted to be given a varying spacing by being mounted upon extensible lazy tongs permitting them to be placed directly upon the reels.

115 In testimony whereof I affix my signature.

SAMUEL WALKER.
